UNITED STATES PATENT OFFICE.

JAMES M. ABBOTT, OF WATERBURY, CONNECTICUT.

DESIGN FOR A BOTTLE-TAP HANDLE.

SPECIFICATION forming part of Design No. 15,253, dated August 19, 1884.

Application filed April 24, 1884. Term of patent 7 years.

To all whom it may concern:

Be it known that I, JAMES M. ABBOTT, of Waterbury, in the county of New Haven, and in the State of Connecticut, have invented a certain new and useful Design for Bottle-Tap Handles; and I do hereby declare that the following is a full, clear, and exact description thereof, reference being had to the accompanying drawing, in which is shown in elevation a view of a bottle-tap handle formed in accordance with my invention.

The object of my invention is to provide a new and ornamental design for bottle-tap handles; and to this end it consists in the handle of the form and configuration as hereinafter described, and more specifically set forth in the claims.

In the drawing, A designates the handle, on the upper end, B, of the tap-shank. This handle is in the form of an elephant. As shown in the drawing, the elephant stands with one fore foot, C, and one hind foot, D, on the top B of the tap, the other fore leg, E, being lifted and extended forward, while the other hind leg, H, is lifted and extended rearward. The trunk G is represented as curled upward and forward. In the end of the trunk is shown an opening, L. In the side of the elephant is shown an opening or recess, M. The construction of the valve-operating mechanism, and the connecting means between the movable tail forming the valve-handle and such mechanism,

I do not describe or show herein, as I cover them fully in an application for mechanical patent filed by me on the 19th day of July, 1884, No. 138,210.

Having thus fully set forth the nature of my invention, what I claim as new is—

1. The design for a bottle-tap handle, the same consisting of the shank-head B and the handle A, having the shape of an elephant, as shown and described.

2. As a design for a bottle-tap handle, the figure of an elephant having a recess or opening in its side, as shown and described.

3. The design for a bottle-tap handle, consisting of the shank-head B and the handle A, having the shape of an elephant, provided with an opening in the end of his trunk, as shown.

4. As a design for a bottle-tap handle, the figure of an elephant standing with one fore foot and one hind foot on the top of the tap, and with one fore leg and one hind leg extended forward and rearward, respectively, as shown and described.

In testimony that I claim the foregoing I have hereunto set my hand this 12th day of April, A. D. 1884.

JAMES M. ABBOTT.
